UNITED STATES PATENT OFFICE.

FRIEDRICH G. DIEKE, OF JOHNSON CITY, NEW YORK.

BRUSH HOLDER FOR DRAINING BRUSHES.

Application filed October 14, 1921. Serial No. 507,653.

To all whom it may concern:

Be it known that I, FRIEDRICH G. DIEKE, a citizen of the United States, residing at Johnson City, in the county of Broome and 5 State of New York, have invented certain new and useful Improvements in Brush Holders for Draining Brushes, of which the following is a specification.

My invention relates to improvements in 10 brush holders, for draining calcimining and paste brushes especially, and it has for its object to provide a removable collapsible and adjustable brush holder for brush draining purposes and one which will removably 15 hold the brushes while draining in a pail or other receptacle. With these objects in view, my invention consists in certain novel features of construction and arrangement of parts as will be more clearly hereinafter 20 described and pointed out in the claims, reference being had to the accompanying drawings in which:

Fig. 1, is a side view of my device.

Fig. 2, is a rear view of my device.

25 Fig. 3, is a front end view of my device.

Fig. 4, is a side view of my device unfolded.

The same reference characters denote like parts in each of the several figures of the 30 drawings. In carrying out my invention I provide a holder support "A" which may be of wood or metal. Having mounted on its front end the projection B, which has parallel therewith and pivotally mounted 35 thereon an arm C, on which arm C, I have mounted or formed integrally therewith or a part thereof, a spring grip D, having projected therefrom the two parallel spring plates 3.3', and on the inner face of 3' I have 40 mounted therein the set screw 4, on the inner end of which I have pivotally mounted a face plate 5; between the projection B and the arm C, I have the pivot 6. On support "A" I have pivotally mounted the angular 45 rests 7.7 mounted parallel to each other, and having on their outer edges the downward projecting lug 8; at the rear end of support "A" I have the support E, having hinged connection with "A" by means of the hinge 50 9. Mounted on support E, I have the vertical lugs 10.10 in pairs opposite each other and between each I have mounted the jaws 11.11 in curved outline forming between them the recess 12. Projected through the 55 interior of support E, I have the parallel tubular opening 13.13 and 14.14. Beneath the

support E, I have the horizontal bar 15, from the ends of which I have projecting the vertical guides 16.16 which project into the opening 13.13. Mounted on the under side 60 of the pivoted jaws 11.11 I have the wires or rods 17.17 connected with said jaws in any convenient manner on the lower ends of which I have mounted the coil springs 18.18 which coil springs are connected in any convenient manner with the bar 15. Pivots 65 mounted on the under side of support E, I have the threaded rod 19. Having thread connection with the bar 15, and on the lower end of which I have mounted a turn button 20; 70 on the inner face of support E I have mounted the eye 21, and on the side of support "A" I have mounted the hook 22, adapted to hook into the eye 21. In the operation of my device when I wish to use the device for 75 draining a brush I clamp the support on the side of the pail F, by placing the spring clamp D over the edge of the pail and turn up the thumb screw 4, until the device is firmly held in position; I then adjust the 80 support A to its proper or convenient angle, by loosening the clamping screw 6' and raising or lowering the support A until it is in its proper position; I then clamp it in 85 position; by turning the screw 6'; I then turn the rests 7.7 to a right angle position with the support A; the hinged support E being held in vertical position by means of the hook 22; I place the brush on the support, by placing the handle G between the 90 spring jaws 11.11; and the body of the brush on the rests 7.7 in a position to project over the pail F for draining; the tension of the springs 18.18 are adjusted by turning the clamping screw 20, which draws down or raises the bar 15; when I wish to arrange the device for shipment, I unhook the support E from the hook 22, and turn it into a horizontal position, as shown in Fig. 4; I turn the rests 7.7, back into alignment with support A; I loosen turn screw 6' and turn the clamp D into horizontal alignment with the support A; thus placing the device in form 95 for packing or shipment.

Thus having described my invention what 105 I claim as new and for which I desire Letters Patent is as follows:

In a brush holder for draining calcimining and other brushes—a support having mounted on its upper surface vertical pivotal 110 parallel rests, adapted to be positioned horizontally at right angles to the sides of the

support, an adjustable pivotal clamping member mounted on the front end of support A, a hinged support member E mounted on the rear end of support A, adapted to be removably held in a vertical position, vertical spring jaws pivotally mounted on the upper edge of support E, coil springs vertically and movably mounted in support

E, and connecting with said jaws, means mounted in said support E and projecting below the same, for adjusting the tension of said springs.

In testimony whereof, I have affixed my signature.

FRIEDRICH G. DIEKE.
